ABSTRACT OF THE DISCLOSURE

An apparatus for winding or unwinding continuous webs of non-conductive material, the apparatus incorporating an alpha particle-emitting device directed toward a winding or unwinding roll of web beyond the point of tangency between the web and roll.

BACKGROUND OF THE INVENTION

Field of the invention

Electrostatic charges accumulate on the surfaces of continuous, non-conductive webs during various operations. Relatively large charges are generated during the winding and unwinding of rolls of such webs, with lesser charges being created as the webs pass over drive and idler rollers. Static charges in wound rolls frequently cause sudden electrical discharges which are, at least, annoying and sometimes dangerous to personnel at work in the area. These electrical discharges can also cause physical damage to the web, such as discoloration, marking, crimping and, on light-sensitive webs, static markings are revealed upon development of exposed webs.

Description of the prior art

The prior art teaches the use of gas flames, X-rays, cathode rays, high-potential electrical sources, and various radioactive sources as means of ionizing the air surrounding them for the purpose of destaticizing electrically non-conductive surfaces. However, the prior art expressly discloses or implies that the surface to be electrically neutralized be in the immediate vicinity of the ionizing source, i.e., within a few inches from the alpha particle sources that have been proposed for use adjacent a nip between a web and roll.

It has been found that if an alpha particle-emitting device is directed onto a web before it is wound, the average electrostatic charge on the wound roll is much greater than if the device is directed onto the web on the roll after the point of tangency. The difference is manifold, which is quite unexpected. Similar results are obtained during unwinding with the apparatus described herein.

SUMMARY OF THE INVENTION

The apparatus of the invention comprises a rotating roll of web of non-conductive material having in combination therewith adjacent the roll beyond the point of tangency between the moving web and the roll an alpha particle emitting device directing particles toward the roll of web. One or more alpha particle emitting bars which extend across the width of the web can be used. The invention also comprises a process as described above.

BRIEF DESCRIPTION OF THE DRAWING

FIG. 1 is an isometric view of one form of apparatus of the invention, and

FIG. 2 is an elevation of a multiple yoke winding apparatus of the invention.

Referring to FIG. 1, a web W which is being wound on a suitable core (not shown) mounted on suitable vertical supports 1 and 2 attached to base 3. The apparatus

2

has an alpha particle emitting bar 4 which extends across the roll. The bar is approximately 45° from the point of tangency between the web and the surface of the roll. The ends of the bar are fastened by suitable means to arms 5 and 6 which extend laterally from and are attached to the vertical supports.

In FIG. 2, the web handling device comprises multiple yokes 10 which are attached to the ends of a suitable rotatable hub or shaft 11 that can be journaled in any suitable support frame (not shown). The ends of the three radial arms are adapted to support respective roll cores or spindles 12, 13 and 14. A roll of web W is shown as being wound onto core 14 while a fully wound roll is shown on core 12 and is in position for removal. Core 13 has been placed on the remaining arm and upon rotation of the yoke can be brought into winding or unwinding position as is common in the art of winding and unwinding webs. Alpha particle emitting bars 15, 16 and 17 are placed adjacent the hub or shaft of the yokes.

The web passes from a suitable source (not shown) which in the case of photographic film or paper could be from an emulsion coating apparatus or a drying apparatus. It passes over guide rollers 18 and 19 and between the yokes so that they extend across the width of the web. The bars emit alpha particles so that an ion cloud is formed in the atmosphere adjacent the roll of web and remove static charges on each lap of the web as it is wound onto the web.

For comparison, as described below, alpha particle emitting bars 20 and 21 are shown close to the web before it is in the form of a web roll.

It has been found that good results can be obtained when the bar or bars are spaced 5 to 14 inches from the surface of the roll of web.

The table below indicates the effectiveness of applicant's construction when incorporated in a rewind apparatus as shown in FIG. 2, which is winding a clear polyethylene terephthalate web.

The measurements of electrostatic charge level were made with a transducer which converts the electrostatic signal into an A-C signal, which is measured by a standard A-C voltmeter. The transducer was held approximately one inch from the roll surface and measurements were taken at three points across the width of the web, every one thousand feet of web wound. During the course of the experiment the rotational speed of the winding roll varied from approximately 20 to 55 r.p.m.

Experiment No.	Description	Average electrostatic charge on roll #13 (kv.)
1	Emitters 15* and 16* were taped to prevent emission. Emitter 17* was moved to position 21, approx. 2 in. from the web, near idler roll 19.	18.0
2	Emitters 15, 16, 17 were placed as shown in FIG. 2 and all were operating. Generator to winding roll distance varied from 14-5 inches.	5.0
3	Same as Exp't. #1, except emitter 17 was moved to position 20, approximately 3 in. from the web, 3 ft. from winding nip point.	9.0
4	Emitters 15, 16, 17, all mounted in position 20, approximately 3 inches from the web, 3 ft. from winding nip point.	7.0
5	Same as Exp't. #2 except emitters 15 and 16 were taped to prevent emission.	5.0
6	Emitters 15, 16, and 17, all mounted in approximately position 17 in FIG. #2 and all directed toward roll 14.	3.0

* The alpha particle emitters used in this experiment were 3M Brand Static Eliminators, Model 7B8F, 1½ millicuries/m. activity.

The above table indicates that in the three cases (2, 5 and 6) where the alpha particle emitter was in a position to create an ion cloud adjacent the winding roll the electrostatic charge build-up was lower than when the

alpha particle emitter was directed at the web alone before the web was wound onto the winding roll. When no alpha particle emitters were used either on winding roll or the web alone, the electrostatic charge on the winding roll rapidly built up to the saturation point of approximately 25 kv., within 100 to 200 feet of web wound.

Preferably the bar is placed around the roll a substantial distance from the point of tangency and from the nip between the roll and web.

The process and apparatus of the invention can be used with various webs of non-conductive material such as paper, resin coated, e.g., polyethylene coated paper, cellulose derivative, e.g., cellulose acetate, cellulose acetate propionate and cellulose acetate butyrate polystyrene, polyvinyl acetate and polyester, e.g., polyethylene terephthalate. Such webs accumulate static charges. These webs can, of course, be coated with various layers, e.g., vinylidene chloride copolymer layers and/or various photographic layers. For example, the invention can be used with high speed negative photographic films provided the web is in motion during passage by the bars. A safe residence time for such a photographic film in the field of a 1.5 millicurie/inch alpha particle emitting bar is approximately 30 seconds at a web generator distance of 2 inches.

The embodiments of the invention in which an exclusive property or privilege is claimed are defined as follows:

1. A web winding apparatus comprising spaced yokes having a plurality of radial arms adapted to support rotatable rolls of non-conductive web material, said yokes being mounted on a hub extending between the yokes, an alpha particle emitting bar mounted on the hub adjacent each roll of web, and disposed so as to emit particles toward the axis of the respective roll.

2. A web winding apparatus according to claim 1 wherein there are three equally spaced radial arms.

3. A web winding apparatus according to claim 1 wherein there are three equally spaced radial arms and there are guiding means for feeding the web to the roll in a vertical direction when two arms have their axes in the lowermost common horizontal plane.

4. A process which comprises winding a web of non-conductive web material that accumulates static charges into a roll, directing alpha particles onto the outer convolution of the roll as it rotates, the particles emanating from a source 5-14 inches from said convolution and being directed to an area around the roll a substantial distance from the point of tangency between the web and the roll.

5. A process which comprises winding a web of non-conductive web material that accumulates static charges into a roll, directing alpha particles onto the outer convolution of the roll as it rotates, the particles emanating from a source 5-14 inches from said convolution and being directed to an area around the roll a substantial distance from the point of tangency between the web and the roll, and a substantial distance from the nip between the web and roll.

10 6. A process according to claim 5 wherein the particles are directed from a source extending across the width of the roll.

15 7. A process according to claim 5 wherein said web is a polyethylene terephthalate web.
